APPARATUS FOR FINISHING WOOD

Leslie Hess Jones, Memphis, Tenn., assignor to
 E. L. Bruce Company, Memphis, Tenn., a corporation of Delaware

Application October 7, 1950, Serial No. 188,970

1 Claim. (Cl. 118—248)

1 This invention relates to an improvement in apparatus for the finishing of wood and, more particularly, for the factory finishing of wood flooring in the form of strips, blocks, and the like.

Heretofore wood flooring, in the form of strips, blocks, and the like, has been finished in the factory so that when laid no further finishing operation is required.

In the factory finishing of wood flooring, it has been customary to apply to a surface of wood flooring a penetrating seal finish composition, in distinction from a surface coating such as a varnish or shellac, work the finishing composition into the pores of the wood, remove excess finish composition, apply heat to dry the finish and finally wax the surface of the wood to complete the finish.

Apparatus for the factory finishing of wood flooring has generally comprised a continuously moving conveyor, as an endless belt, which carries the wood flooring into operative relation with various instrumentalities successively arranged with respect to the conveyor and designed to effect the several operations involved in the finishing operation. Such apparatus is illustrated and described, for example, in U. S. Patent No. 2,341,161, to which reference is hereby made.

The apparatus heretofore used in factory finishing has proved generally efficient. However, it has been found that in the application of the finishing composition to the surface of the flooring, which is usually accomplished by spraying, a substantial amount of the composition is deposited on the surface of the conveyor, usually an endless belt, through gaps between the ends or edges of the flooring units, as strips, blocks, or the like, and building up on the conveyor prevents the flooring units thereon from presenting a flat horizontal surface required for proper finishing, and otherwise negatives efficient operation of the apparatus, requiring frequent interruption of the finishing operation for cleaning of the conveyor and waste of finishing composition.

Now in accordance with this invention, there is provided an improvement in apparatus for factory finishing, more particularly with respect to that portion of the apparatus designed for the application of the finishing composition.

This invention contemplates the provision of means whereby the finishing composition is applied to the flooring units by means of a roller without interruption of the continuity of the flooring units through the apparatus.

2 Details involved in this invention will be made apparent in the following description when read in conjunction with the following drawings, in which:

5 Figure 1 is a plan view of a portion of a conveyor including the roller finishing composition applying apparatus embodying this invention with the upper portion thereof removed;

Figure 2 is a side elevation of the roller finishing composition applying apparatus; and

Figure 3 is a front elevation of the apparatus shown in Figure 2.

Referring to the figures there is shown an endless conveyor belt 6 which overlies a metal sheet 2. The belt is supported at one end of the conveyor by the pulley 7 which is mounted on the side frames 10. At the opposite end of the conveyor the belt is similarly supported. The belt is driven by means of suitable drive motor 8 and speed reducer 9, connected to the pulley 7.

The flooring strips 12 are placed on the belt conveyor 6 and pass under the pressure roller 14 which is mounted on the side frames 10 by means of the adjustable bearing mounts 16. These mounts are adjustable in order that the height of the roller above the conveyor may be adjusted for various thicknesses of flooring strips. The strips are in tongue and groove engagement, as shown in Figure 3, as they pass under the roller coating apparatus shown generally at 18 in Figure 1 and shown in greater detail in Figures 2 and 3.

The roller coating apparatus includes the frame work 20 on top of which is mounted the driving motor 22 and the speed reducer 24 connected together by means of the drive belt 23. The speed reducer is coupled by means of the drive chain 26 to a sprocket rigidly mounted on the shaft mounting the coating of the roller 28. The idler sprocket 25 is employed to adjust 40 the slack in the drive chain 26.

The coating roller 28 has its outer surface 27 coated with a material such as rubber or other suitably yielding material which is resistant to the finishing compositions employed.

45 There is associated with the coating roller 28 the rollers 30 and 32. These three rollers are mounted on shafts which are supported by bearings 29, 31 and 33 respectively, which are fixed to portions of the frame work 20.

The chain 34 engages sprockets fixed on the shafts of each of the three rollers and thus serves to rigidly connect the three rollers in rotating connection. Thus the rollers 30 and 32 are driven at a constant speed with the 55 roller 28, and the three rollers then rotate in

the same direction, namely, counterclockwise as viewed in Figure 2 or in a direction in which the roller 28 would be driven if free to be rotated by the passage of the flooring thereunder.

Suspended below the lower portion of the roller 32 is the trough 36. Fluid finishing composition is maintained in the trough 36 at a sufficient depth so that as the roller 32 rotates, it picks up on its surface a layer of finishing composition.

Suspended from the frame work 20 is the roller scraper 38. This scraper is adjusted to a spaced position from the roller 30 by means of the threaded hanger rods 40 which pass through the cross member 44 which is supported by the frame work 20. By adjusting the butterfly nuts 48, the scraper may be raised or lowered on an arc determined by the fixed brace members 50 and its spacing with respect to the roller 30 which may thereby be adjusted with extreme accuracy.

The frame work 20 of the roller coating device includes the angle members 52 which rest on collars 54 which are rigidly fixed to the supporting rods 56. The supporting rods 56 are threaded through blocks 58 which are fixed to the channel members 60 which rest on the side frames 10. The upper ends of the supporting rods 56 are formed as handles 62, whereby the threaded rods 56 may be conveniently rotated to raise and lower the roller coater with respect to the conveyor in order to provide adjustment of the pressure of the roller 28 upon the flooring strips.

In operation of the roller coater, the wood flooring strips 12 are carried through the coater 33 on the conveyor belt 6. The strips pass under the pressure roller 14 which serves to hold the strips firmly against the conveyor and to secure flat horizontal surfaces of the flooring as they pass under the coating roller 28.

Referring to the rollers 28, 30 and 32 which are of substantially uniform diameter, and which all rotate in the same direction and with substantially equal peripheral velocity as a result of being driven by the chain 34, the roller 32 picks up finishing composition from the trough 36. The roller 30 which is positioned to slight clearance with the roller 32, picks up from the roller 32 a portion of the finishing composition carried thereby. The roller 30 then carries a layer of finishing composition up to and past the scraper 38. The scraper 38 which is adjusted to a fixed dimension from the roller 30 serves to meter or to control the thickness or the amount of the finishing composition which is carried by the roller 30 and is transferred to the roller 28. The roller 28 and the roller 30 are positioned so that their surfaces are barely touching as the two rollers rotate, and thus there is deposited upon the roller 28 a layer of finishing material of uniformly controlled thickness. As the roller 28 proceeds to rotate, this layer of finishing composition is deposited upon the wood flooring strips which are passing thereunder. The speed of the roller 28 is adjusted with respect to the speed of the flooring strips so that the roller rotates at substantially the same or somewhat faster surface speed than the speed of travel of the flooring strips passing thereunder, and the yielding rubber surface of the roller acts to spread and press the coating composition over the surfaces of the wood strips.

Immediately following the coating of the finishing composition on the wood strips, the flooring, which is moving on the belt conveyor, is

brushed by the revolving bristle brush 70 which is driven by the motor 72 through the belt 74. This brush spreads the remaining composition uniformly over the surface of the wood. The flooring next meets the revolving burlap pad buffer 76 which is driven by the motor 78 and the belt 80 and which further uniformly spreads and removes any surplus composition.

Following the operations just described, the 10 flooring enters an infra-red light line 82 in which the finishing composition is set as described more fully in the above mentioned patent application.

It will be apparent that the present invention employs novel roller coating apparatus which applies a uniform coating of a finishing composition to wood flooring strips as they are passed continuously along a moving conveyor. The rubber covered roller makes possible the application of the coating composition with a uniform and controlled roller pressure, and by adjusting the peripheral speed of the coating roller to a speed slightly greater than the speed of the wood flooring strips, a wiping action may be obtained between the rubber surfaced roller and the flooring strips which serves to apply the coating to the wood flooring strips with a highly desirable pressing or squeegeing action.

It will be apparent that various modifications 30 may be made in the foregoing embodiment of this invention without departing from the scope of the invention as set forth in the following claim.

What is claimed is:

In apparatus for the finishing of wood flooring units, a longitudinally extending conveyor for conveying wood flooring units, a framework mounted over said conveyor, said framework supporting three rollers rotatably mounted in axially parallel relationship, driving means mounted on said framework and rotating all of said rollers in the same direction, a trough partially surrounding the first of said rollers, said trough containing a coating composition, the second of said rollers being positioned adjacent to the first of said rollers to remove coating composition therefrom, a scraper mounted on said framework adjacent said second roller to control the thickness of coating composition carried by said second roller, the third of said rollers being in engagement with said second roller and removing the layer of coating composition therefrom, said third roller having a yielding rubber surface for engagement with said flooring units, and means for adjusting the distance between said third roller and said conveyor.

LESLIE HESS JONES.
